[57] **CLAIM**

The ornamental design for a combination cutting and ironing board, as shown and described.

DESCRIPTION

FIG. 1 is a front elevational view of a combination cutting and ironing board showing my new design; FIG. 2 is a top plan view thereof; FIG. 3 is a rear elevational view thereof; FIG. 4 is a left side elevational view thereof, the right side being the mirror image thereof; and, FIG. 5 is a bottom plan view thereof.

The crosshatched pattern, which is partially shown for ease of illustration in FIGS. 1 and 3-5, represents a conventional fabric and is understood to repeat throughout the areas indicated.

FIG. 1

FIG. 2

FIG. 4

FIG. 3

FIG. 5
